UNITED STATES PATENT OFFICE.

ARTHUR E. HANDY, OF NEW YORK, AND SAMUEL G. MARGLES, OF BROOKLYN, NEW YORK, ASSIGNORS TO OTIS ELEVATOR COMPANY, OF JERSEY CITY, NEW JERSEY, A CORPORATION OF NEW JERSEY.

SAFETY DEVICE FOR ESCALATORS.

Application filed August 30, 1922. Serial No. 585,956.

To all whom it may concern:

Be it known that we, ARTHUR E. HANDY, a citizen of the United States, residing at New York, county of New York, State of New York, and SAMUEL G. MARGLES, a citizen of the United States, residing in Brooklyn, in the county of Kings and State of New York, have invented a new and useful Improvement in Safety Devices for Escalators, 10 of which the following is a specification.

Our invention relates to inclined endless conveyers, more particularly of the step type commonly known as escalators. Essentially the invention consists in the provision of a safety device such as an emergency brake for controlling the escalator to stop it when certain undesirable conditions arise during the operation of the same.

The invention consists in the apparatus 20 hereinafter described and illustrated in the accompanying drawing in which:

Figure 1 is a side elevation of an end portion of an escalator.

Figure 2 illustrates the emergency brake 25 as it appears looking at its outside side together with a fragmentary part of the escalator driving sprocket, the view also embodying an electromagnet and pawl, a pair of switches and a governor, all of which are 30 associated with the emergency brake.

Figure 3 illustrates the emergency brake as it appears looking at its inside side with the escalator driving sprocket shown in part.

Figure 4 illustrates a sectional view of 35 Figure 3 on the lines 4—4.

Figure 5 illustrates diagrammatically a system of circuits that may be used to describe the operation of our invention.

Like reference characters denote similar 40 parts in all of the figures.

Reference being had to Figure 1, an escalator of which only a part is shown comprises a series of steps A which form an endless movable platform or surface connecting 45 different floor levels (not shown). Each step has a pair of rear wheels 1, and a pair of front wheels 2, and are adapted to travel respectively on suitable track rails such as 3 and 4. There is provided for the purpose 50 of driving the steps, an endless chain 5, arranged on a center line coinciding with the center of a sprocket 6. A similar chain 5 on the escalator's other side is arranged in the same manner with a similar sprocket 6 also

on the escalator's other side. The chain comprises a series of links pivotally connected with the front wheel axles of the steps to form the endless chain 5. The sprockets are constructed with cut-out portions such as 7, to accommodate the front step wheels 2, and 60 cut-out portions such as 8, to accommodate the chain. A driving sprocket 9 fastened to the shaft of the sprocket 6 is adapted to drive the escalator and may be driven by any suitable source of power, for instance, by an 65 electric motor M, as shown.

Coming now to the particular part of the present invention, an emergency brake B of the multiple disc type is mounted on the driving shaft together with the driving 70 sprocket 9 and the sprockets 6, and is adapted to rotate with them. Referring to Figures 3 and 4, the brake comprises a movable member 10 on the outer rim of which there are cams 11 and teeth 12, and in different planes from each other. To the inside of the member 10 there is keyed by keys 13, that are held in place by screws 14 in the member and screwed to its key, a circular disc member 15. To another movable member 16 there is keyed by keys 17, that are held in place by screws 18 in the driving sprocket 9 and screwed into its key, another circular disc member 19. To the member 16 there is fastened bolts 20 which also pass 80 through the driving sprocket 9. Each bolt 20 has a spring 21 thereon, the bolts and their springs pulling the member 16 and the driving sprocket 9 together. Since the member 16 is pulled to the sprocket 9 by the 85 springs 21 through their bolts 20, the member 16 in turn jams, so to speak, the members 10, 15 and 19 and four wooden circular discs 22 between them, also to the driving sprocket 9. The frictional engagement obtained by the wooden discs 22 causes the emergency brake, of which they are a part, to turn with the driving sprocket 9 when it is made to rotate.

Referring to Figure 2, the emergency 100 brake by its cams 11 is adapted to operate a pendulum governor C which comprises a crooked arm 23 loosely journaled at 24 to a frame work 25 of the escalator. The arm 23 carries a roller 26, which is kept constantly in contact with the cams 11 of the brake by a weight 27 at the lower end of the arm when the escalator is running 105

- normal. When the escalator overspeeds in either direction the impulse of the cams on the roller is more than the weight will balance and the roller therefore leaves the cam.
- 5 When the overspeed reaches a predetermined amount the governor arm 23 and its roller 26 is thrown out a sufficient amount to cause a finger 28 formed at the upper end of the arm 23 to contact with a bolt 29 carried by an arm 30 loosely journaled at 31 to a switch D and trip a trigger 32 of the switch hinged at 33. It will be noted that the trigger 32 has a projection 321 extending downwardly and
- 10 normally resting upon a projection 301 on arm 30. Upon movement of the arm 30 the projection 301 passes from beneath the projection 321 and allows the trigger 32 to drop, which in dropping breaks contact by
- 15 a pair of contact fingers 34 fastened to the trigger with a pair of electrical contacts 35 in the switch, which will cause the escalator driving motor to be stopped as will be seen hereinafter.
- 20 25 Still referring to Figure 2, an electromagnet E, having a winding 36, is fastened to the escalator frame work 25, and is adapted to operate a pawl 37, the pawl being loosely journaled to a movable core 38 of the electromagnet and also hinged at 39 to the escalator frame work 25. In the Figure 2 the electromagnet is shown as energized and by its movable core 38 is holding the pawl 37 free from the teeth 12 on the member 10 of the
- 25 30 35 40 45 50 55 60 65 70 75 80 85 90 95 100 105 110 115 120 125 130
- brake which it is adapted to engage when the electromagnet is deenergized as will be seen hereinafter. The pawl, when held away from engagement with the teeth 12, holds closed a switch F fastened to the frame work of the escalator by a trigger 41 of the switch resting on the pawl. A pair of contact fingers 42 fastened to the trigger engages a pair of electrical contacts 43 when the switch is in a closed position.
- 45 Referring to Figure 5, the operation of the apparatus is as follows:
- Assuming that the escalator overspeeds in an ascending direction, which in the present invention is in a direction to the observer's right, to a predetermined amount which will cause the governor C to be moved aside by the cams 11 on the brake member 10 and trip the trigger 32 of the switch D and open the connection between the contacts 35 of the switch. The contacts are in circuit to the winding 36 of the electromagnet E and when they are opened cause the winding 36 to become deenergized, the electromagnet in becoming deenergized opening the switch F, by the pawl fastened to its movable core 38, the trigger 41 of the same dropping down and opening the electrical connection between the contacts 43 which are in circuit to the winding 44 of an electromagnet potential switch G which, when it opens, opens

the supply circuit to the escalator driving motor and causes its brake B' to be applied to stop it.

The brake B' as diagrammatically shown comprises a brake shoe 46 which is carried by core 47 and has a spring 48 for applying it and a solenoid 49 for retracting the core 47 for releasing the brake. When the switch G is closed a circuit is made from the positive side of the source, by wire 50, through solenoid 49, and by wire 51 to the negative side of the source, and when the switch G is opened the solenoid is de-energized and the spring will apply the brake.

The present apparatus is adapted to operate when another undesirable condition occurs, namely the breaking of the escalator driving chain 45, which may cause a reversal of the escalator, at such a time and when the speed of the reverse direction of travel of the escalator reaches a predetermined value the governor will operate as before, the pawl 37 at this time when released will engage the teeth 12 on the member 10 holding the member stopped, the frictional engagement of the brake, by its wooden discs 22, with the driving sprocket 9 will cause it to be slowed down and stopped. At the same time the emergency brake B is applied so also is the brake B' of the escalator driving motor applied to the motor to stop it.

In brief, if the escalator exceeds the speed designed for its proper normal operation due to high voltage or breaking of the driving chain, the escalator will be automatically slowed down through the action of the governor, and stopped.

One skilled in the art may make obvious changes in the details and arrangement of parts without departing from the spirit and scope of our invention, and we wish therefore not to be limited to the precise arrangement and details as are herein illustrated and described.

What we claim as new and desire to secure by Letters Patent of the United States is:

1. In combination with the driving mechanism for a conveyor, a brake drum cooperating with said driving mechanism and provided with teeth, and a pawl adapted to engage said teeth for stopping the conveyor.
2. In combination with the driving mechanism for a conveyor, a brake drum operatively connected with said driving mechanism, means in the connection between said brake drum and driving mechanism adapted to yieldably resist relative rotation of the drum and driving mechanism, and means adapted to engage and hold said drum whereby the driving mechanism may be brought to a stop.
3. In combination with the driving mechanism for a conveyor, a brake drum operatively connected with said driving mechanism and provided with teeth, means in the

- connection between said brake drum and driving mechanism adapted to yieldingly resist rotation of the drum with respect to the driving mechanism, and a pawl member 5 adapted to engage the teeth on the brake drum for holding it and thereby bring the driving mechanism to a stop.
4. In an electric power operated escalator, a device to control excessive speed of the escalator, said device comprising a switch adapted to be opened in case of excessive speed of the escalator and effect the interruption of the driving power for the escalator, a part adapted to be operated by the operation of the escalator to effect the opening of the switch in case of excessive speed of the escalator, a ratchet adapted to be operated by the operation of the escalator, a stationary pawl adapted to be released to engage 10 the ratchet, and an electromagnet to hold the pawl out of engagement with the ratchet until released in case of excessive speed of the escalator.
5. In the electric power operated inclined conveyer art, involving a brake for the conveyer, a safety device comprising a pawl and ratchet, a switch adapted to control the engagement of the pawl with the ratchet and the driving power for the conveyer, cams, 15 and a governor adapted to be operated by the cams, said switch adapted to be opened by said operation of the governor, and permit the pawl and ratchet to engage each other, and apply the brake to the conveyer.
6. In the electric power operated escalator art, an emergency brake, comprising a rotatable multiple disc brake having a member with cams thereon, a governor adapted to be actuated by the cams on the said member in revolving, an electric switch adapted 20 to be opened by the governor, an electromagnet adapted to be deenergized by the governor, and a pawl adapted to be actuated by the deenergizing of the electromagnet, and a second switch adapted to be opened by said pawl to open the circuit to the electric power for stopping the escalator.
7. In the electric power operated escalator art, an emergency brake, comprising a rotatable multiple disc brake having a member with cams and teeth thereon, a governor adapted to be actuated by the cams on the said member in revolving, an electric switch adapted 25 to be opened by the governor, an electromagnet adapted to be deenergized by the said switch in opening, and a pawl adapted to be actuated by the deenergized electromagnet, to engage the teeth on the said member to apply the emergency brake to stop the escalator, and a second switch adapted to be opened by said pawl to open the circuit to the electric power for stopping the escalator.

In testimony whereof, we have signed our names to this specification.

ARTHUR E. HANDY.
SAMUEL G. MARGLES.
